Specification of Letters Patent.

Patented Mar. 20, 1917.

Application filed April 8, 1912. Serial No. 689,187.

To all whom it may concern:

Be it known that we, OSCAR PATRIC OSTERGREN, a subject of the King of Sweden, and a resident of No. 431 Throop avenue, 5 Brooklyn, New York, and EDWIN LUNDGREN, a subject of the King of Sweden, and a resident of No. 127 Clinton avenue, Brooklyn, New York, have invented certain new and useful Improvements in Furnaces, of which 10 the following is a specification.

Our invention relates to furnaces in which the fuel is introduced on the underfeed principle, and employing an inclined elongated fuel retort or multiples thereof alternating 15 with twyters to supply air under pressure to the fuel bed and consists of a primary feeding mechanism located externally of the retort and a secondary feeding mechanism located within the retort in combination with 20 means to discharge the ashes and refuse. In order to obtain a maximum of efficiency in furnaces of this type fresh fuel introduced into the fire box from a hopper is moved forward along the length of the receptacle 25 or retort by means of fuel rams or plungers which reciprocate in the retort and constantly supply fresh fuel thereto, the necessary air supply for the fuel being discharged through twyters adjacent to the retort. 30 One of the objects of our invention is to provide improved means for feeding the fuel into the retorts so that the fuel can be fed to any desired point of the fuel bed under the operator's control and also to enable agitation 35 of the fuel bed in variable directions as distinguished from the present constructions in which the feeding of the fuel and the agitation of the fuel bed is confined to one or two single points and always in the same 40 plane.

A further object of our invention is to provide the air inlet pipe through which air is introduced from beneath, approximately centrally of the entire fuel bed and to provide 45 an air chamber located substantially beneath the entire fuel bed whereby air in a desired quantity may be distributed to any point along the entire area of the fuel bed.

A further object of our invention is to 50 form the fuel rams or plungers in a manner whereby the fuel will be given not only the desired forward movement but will also obtain the desirable upward movement and increase agitation of the fuel bed.

The further objects of our invention will 55 be understood by reference to the drawings and the detailed description which follows.

In the accompanying drawings Figure 1 is a longitudinal section through one of the retorts forming our underfeed furnace; Fig. 60 2 is a like view showing a portion of the bridge wall and the centrally located air inlet pipe for the introduction of the air under pressure; Fig. 3 is a plan view of our improved furnace showing the mechanism for 65 actuating the plungers or rams and also showing the twyters, the retorts and, in dotted lines, the conduits or pipes for supplying and conveying heated air to the top of the fuel bed as will hereinafter appear; Fig. 4 70 75 is a longitudinal section taken through the line 4—4 of Fig. 3 and showing the twyters as preferably employed in our improved furnace; and Fig. 5 is a cross-sectional view taken on line 5—5 of Fig. 4.

We shall first describe the mechanism and operation of our improvement in feeding the fuel into the retort and over the twyters. In the accompanying drawings 1 represents a ram block which is cylindrical in form. This 80 ram block reciprocates in a ram box 2, its reciprocal movement being imparted through the connection rod 3 which is connected to a revolving crank 4 (Figs. 2 and 3). This 85 crank receives its revolutions by its connection to a worm gear 4^a which rotates through its engagement with a worm 4^b whose rotations are imparted by any suitable power connection. The ram block 1 during its forward movement in an inclined plane enters 90 the retort 6 and through its wedge shaped face 5 progressively agitates forwardly and upwardly the fuel supplied to the retort from the hopper 7. The utility and function 95 of this arrangement of a wedge shaped or concaved ram face is to give the mass of fuel a progressive agitation and impart to the fuel a feeding movement in an upward direction during the forward motion in the retort, resulting eventually in its distribution 100 over the twyters adjacent to the retort. By this wedge shaped formation of the ram block 1, the resistance of the fuel is moreover greatly diminished, the fuel bed is broken up and the disadvantage of too 105 densely packing the fuel in the retort is wholly avoided.

For the purpose of actuating our im-

proved auxiliary feeding mechanism herein-after described, we connect to the primary ram block 1 a rod 9, extending substantially the whole length of the retort 6, said rod 9 being secured at its other end to a wedge shaped rear ram block 11. By means of this positive connection of the primary and rear ram blocks the reciprocations of the former will result in like reciprocations of the latter within the retort 6.

10 Intermediate of the ram blocks 1 and 11 a ram block 12 is secured upon the reciprocating rod 9, the front face of said ram block 12 being likewise wedge shaped and moving in unison with the ram blocks 1 and 11 by reason of its positive connection to the reciprocating rod 9. This intermediate ram block 12 is located in co-operative relation to a fuel deflecting plate 13 which, 15 as shown in Fig. 1 is located beneath the ram block 12 and extends substantially throughout the width of the retort or fuel chamber 6. This fuel deflecting plate 13, as shown in the particular construction of 20 the drawings is slotted at 14 to permit passage therethrough of the reciprocating rod 9 and is pivotally mounted on a journal 15 as an axis whereon it may be swung to attain any desired height in the retort. The 25 fuel guiding surface of this fuel deflecting plate 13 is preferably concaved, as shown at 13^a. The hand operated means whereby the fuel deflecting plate 13 may be adjusted to the desired position as to height in the retort, comprises a screw and nut engagement 30 16 and a shaft 17, hand wheel 18, whereby the turning of the hand wheel will cause the screw thread either to swing the fuel deflecting plate upwardly or downwardly. It 35 will be understood, that any other or equivalent means may be employed to give the fuel deflecting plate the desired adjustment or that the ram block 12 may be constructed to have a swinging movement relatively to 40 the fuel deflecting plate.

45 The operation of our improved fuel feeding device is as follows:

The fuel is introduced to the retort 6 through the hopper 7 and rests upon the 50 bottom plate 6^a of the retort, the ram blocks 1, 11 and 12 being in their retracted positions. Through power imparted to the connection rod 3 the three ram blocks are then moved forward. The fuel supplied through 55 hopper 7 to the upper end of the retort 6 is now moved forward and upward by the forward movement of the ram block 1. During the rearward movement of the ram block 1 a further supply of fuel is admitted 60 through hopper 7. During the subsequent forward movements of the ram block 1 the fuel advanced by the ram block 1 during the prior forward movement is picked up by the forward movement of the intermediate 65 ram block 12 and is carried thereby for-

wardly and upwardly along the concaved surface 13^a of the fuel deflecting plate 13. During the further reciprocation of the ram blocks 1, 11 and 12 the fuel carried by the ram block 12 will drop into the portion 11^a 70 of the retort 6 below the fuel deflecting plate 13. When this space 11^a of the retort is substantially filled the ram block 11, being provided with a wedge shaped face 11^b will in its retracting movement burrow 75 through the fuel lying therein and through the wedging action cause its passage into the end portion 11^c of the retort, while during the succeeding forward movement of the ram block 11 the fuel will be advanced to 80 the lowermost portion of the retort. Further reciprocations will result in a similar ram movement for the fuel through the ram blocks 1, 11 and 12 until the retort is completely filled and the fuel thereafter 85 overflows over the twyers 8 adjacent to the retort. The continued reciprocations of our ram blocks after the retort is filled and the twyers covered with fuel results in the continuous feeding of the fuel and the agitation required for the maximum of efficiency. If desired, in starting the furnace the fuel deflecting plate 13 may be in its depressed position so that the regulation of the fuel 90 will be accomplished without its coöperation and entirely by the stroke of the ram blocks.

The main difficulty which has been found in furnace stokers of the kind here generally referred to has resided in the fact 100 that with the horizontal ramming stroke of the rams the portion of the fuel bed nearest the hopper would be built up to an excessive height and density in the retorts and over the twyers while the twyers more remote from the hopper would be but sparsely covered with fuel resulting in the retardation of combustion at the front part of the furnace in view of the fact that the air would but slowly penetrate the mass of fuel 110 densely accumulated toward the front part of the furnace. This difficulty is entirely overcome by our present invention wherein the height of the fuel deflecting plate regulates the depth of the fuel at any portion of 115 the fuel bed. While we have herein shown this fuel deflecting plate as adjustable it will be understood that in given cases the same may be fixed and effectively control the distribution of fuel. A further difficulty in 120 prior structures has resulted from the density of fuel produced by the impacting of ram blocks having a vertical face, tending to compress and pack the fuel. The wedging action of the ram blocks here described 125 overcomes this objection and secures the desirable result of constant agitation of the fuel in the course of feeding the load into the various portions of the retort.

We shall now describe our arrangement 130

for the introduction into the furnace of air under pressure. In the prior constructions the forced draft supply is introduced through a "wind-box" transversely underlying the fuel bed near the lowermost portion of the retort and twyers where the fuel bed is comparatively thin and consists largely of burnt-out fuel, ashes and clinkers.

The result of this arrangement is that the forced draft in a straight course passes through the sphere of least resistance, this being the portion of the fuel bed where the fuel is thinnest and almost burnt out. The portion of the fuel bed, on the contrary, nearest the supply hopper wherein the "volatile matter" requires a much greater supply of air and the fuel bed is of greater depth, is in the prior structures inadequately provided for. In our construction we provide a centrally located forced draft pipe 20 beneath and communicating with a chamber 21 underlying the entire series of openings 22 of the twyers 8. The introduction of the air under pressure into the chamber 21 above the draft pipe 20 results in a general and equal distribution of the air throughout the entire series of twyers 8 while the employment of a swinging damper 23 in said pipe 20 permits of the exact regulation of air admission to said chamber 21 as the conditions may require. The bottom plate 23^a of the chamber 21 is provided with the opening 23^b through which this supply pipe delivers its forced draft.

For the purpose of regulating the quantity and pressure of air to be supplied to either the upper or lower portions of the fuel bed, we provide in the underlying chamber 21 a partition wall 21^a extending throughout the width of said chamber 21 and provided with a series of openings 26 and dampers 27 which may be arranged to slide over the said openings 26 by means of hand operated shaft 27^a having a gearing 28 which meshes with a rack 29 secured to the sliding dampers 27, whereby a rotation of the hand wheel will cause the gear 28 to mesh with the teeth of the rack 29 and slide the dampers 27 any desired distance over the openings 26 in said partition wall. When it is desirable in view of the condition of the fuel lying on the lower portions of the fuel bed to increase or decrease the air supply and divert a greater or less volume to the lower portions of the fuel bed, the dampers 27 are manipulated to permit air admission as the condition of the lower fuel bed may require.

A further feature of our improved furnace construction consists in the introduction of heated air by means of pipes 24 which extend lengthwise beneath the twyers 8. At the upper end of the pipe the same is provided with a bent portion 24^a communicating with an upper distributing chamber

25 provided with perforations 25^a through which the air will pass over the fuel accumulated in the upper portions of the fuel bed. The air supplied for these pipes 24 is obtained likewise through the draft pipe 20 and the chamber 21 and by reason of its passage through the chamber 30, formed by a top plate 30^a, rear plate 30^b and bent portion 30^c, will reach the outlet perforations 25^a in a highly heated condition. The bent portion 24^a of the pipe 24 is provided with a damper 24^b which will serve for the regulation of heated air supplied into the upper portions of the fuel bed. As shown in the drawings these pipes 24 are located beneath alternate series of twyers 8 but if desired it will, of course, be understood that these pipes may be located in each of the series of twyers. The advantage of this construction is that the top plate 30^a is protected by the circulation of air beneath it; that the clinkers and ashes passing over this plate may be discharged on to the dumping plate at a low temperature and that the circulating air is heated in the chamber 30 prior to its passage into the pipes 24 and over the upper fuel bed.

Another feature of our invention is the employment of steam pipes 31 adjacent to the side walls of the furnace, these pipes being provided with perforations whereby steam emitted therethrough will prevent the formation of clinkers upon the surface of the side wall and portions adjacent thereto thereby protecting the fire brick of the side walls from the destroying influences of clinker formation and relieving the plungers from the strain of breaking up and overcoming the resistance of such clinker formation. By this means the life of the furnace lining is prolonged and a more even and unimpeded operation of the plungers nearest the side walls is insured.

The pipes 31 project outside of the front wall of the furnace and are provided with the usual valves 31^a to regulate the amount of steam admitted.

We claim:

1. In an underfeed, forced draft furnace, the combination of a fuel support comprising an inclined, elongated fuel retort, twyers adjacent thereto, an air chamber underlying said fuel support and twyers, a partition wall dividing said chamber into a plurality of compartments, means provided in said partition wall for regulating the admission of air from one into the other of said compartments, a conduit in communication with one of said compartments, said conduit extending longitudinally beneath the fuel support, and terminating at a point above the fuel bed to deliver the heated air from said compartment above the fuel bed.

2. In an underfeed forced draft furnace the combination of a fuel support compris-

ing an inclined elongated fuel retort, twyers adjacent thereto, an air chamber underlying said fuel support and twyers, a secondary chamber at the lower end of the retort, a 5 conduit in communication with said secondary chamber, extending longitudinally beneath said fuel support from said secondary chamber and terminating at a point above the fuel bed to deliver heated air at 10 a point above said fuel bed.

3. In an underfeed furnace, the combination of a fuel support, side and end walls surrounding said fuel support and perforated steam pipes adjacent to said side walls 15 and arranged to project steam against said walls above the fuel bearing surface, and means to supply steam to said pipes.

4. In an underfeed furnace, the combination of downwardly inclined, elongated fuel 20 retorts, downwardly inclined fuel supporting surfaces alternately arranged with the retorts, and comprising fuel supporting twyer blocks located in overlapping relation and having their fuel supporting surfaces 25 elevated above the bottoms of the retorts, a fuel hopper communicating with at least one of said retorts, means for introducing fuel from said hopper into said retort below the surface of the fuel maintained on the 30 fuel supporting surfaces, an air chamber underlying the retorts and said fuel supporting twyer blocks, a partition dividing said chamber into a plurality of compartments, means provided within the partition for 35 regulating the delivery of air from one compartment into another, and means for delivering air under pressure to one of said compartments.

5. In an underfeed forced draft furnace, 40 the combination of downwardly inclined elongated fuel retorts, downwardly inclined fuel supporting surfaces alternately arranged with the retorts and comprising fuel supporting twyer blocks located in overlapping 45 relation and having their fuel supporting surfaces elevated above the bottoms of the fuel retorts, means for delivering fuel into the upper ends of the retorts below the surface of the fuel maintained on said fuel 50 supporting surfaces, an air chamber underlying said fuel supporting twyer blocks and said retorts, a partition extending at an angle to the retorts and dividing the chamber into a forward compartment communicating with the upper ends of the fuel supporting surfaces, and a rear compartment communicating with the lower ends of the fuel supporting surfaces, means for delivering air under pressure to the forward compartment, means provided within the partition for establishing communication between the compartments and adjustable 60 means for regulating the flow of air from the forward to the rear compartment.

6. In an underfeed stoker, a downwardly

inclined fuel retort extending from the front to the rear of the stoker, downwardly inclined fuel supporting twyers located on each side of said retort and extending from the front to the rear of the stoker, a hopper 70 communicating with the upper end of the retort, reciprocable means located in the hopper for forcing fuel therefrom into the upper end of the fuel retort, a ram block located in the retort and operatively secured 75 to said means and having its fuel forcing face inclined at an angle greater than a right angle to the bottom of the retort, an adjustable fuel deflector located in the bottom of the retort intermediate the ends thereof, and means for raising and lowering said deflector to different positions.

7. In a furnace, the combination of a longitudinally extending fuel support having a trough-shaped retort formed therein, a ram 85 block for moving fuel into and through the retort, and an adjustable fuel deflector located in the retort within the path of travel of the fuel through the retort and forming a part of the fuel support.

8. In a furnace, the combination of a downwardly inclined fuel support comprising a trough-shaped retort extending from the front to the rear of the furnace and longitudinally extending fuel supporting 85 twyers located on each side of the retort with their fuel supporting surfaces elevated above the floor of the retort, reciprocable ram blocks for introducing fuel into said retort and for moving fuel across the fuel support, 100 and an adjustable deflector located in the bottom of the retort and co-operating with the ram blocks to vary the depth of the fuel bed at different points along the fuel support.

9. In an underfeed furnace, the combination of a downwardly inclined fuel support comprising longitudinally extending trough-shaped fuel retorts, and alternately arranged fuel supporting twyers having their fuel supporting surfaces elevated above the bottoms of the retorts, a fuel hopper communicating with the forward ends of the retorts, means for introducing fuel from said hopper into said retorts below the surface of the fuel bed 115 maintained on said fuel support, a reciprocable fuel ram block having a wedge shaped fuel feeding face located in each retort, and an adjustable fuel deflector located in the bottom of each retort between the fuel feeding means and the ram block.

10. In an underfeed forced draft furnace, the combination of downwardly inclined elongated fuel retorts, downwardly inclined fuel supporting surfaces alternately arranged with the retorts and each comprising removable fuel supporting and air delivery means located in inclined relations and extending from the front of the furnace downwardly to substantially the lower ends of the 130

- retorts and having their fuel supporting surfaces elevated above the bottom of the retorts, means for delivering fuel into the upper ends of the retorts and below the surfaces supporting surfaces, means for delivering air under pressure to the forward compartment, 15 and means for delivering air at a less volume and pressure to the rear compartment.
- 5 face of the fuel maintained on the fuel supporting surfaces, an air chamber underlying said fuel supporting surfaces and said retorts, means extending at an angle to the retorts and dividing the chamber into a forward compartment communicating with the upper portions of the fuel supporting surfaces, and a rear compartment communicating with the lower portions of the fuel sup-
- 10 porting surfaces, means for delivering air under pressure to the forward compartment, 15 and means for delivering air at a less volume and pressure to the rear compartment.
- In witness whereof we have hereunto set our hands in the presence of two subscribing witnesses.
- OSCAR PATRIC OSTERGREN.
EDWIN LUNDGREN.
